(57) **CLAIM**

The ornamental design for a chair with a cupholder, as shown and described.

DESCRIPTION

FIG. 1 is a top perspective view of a chair with a cupholder;
FIG. 2 is a right-side elevational view of the chair with a
cupholder shown in FIG. 1;
FIG. 3 is a top plan view thereof;
FIG. 4 is a front elevational view thereof;
FIG. 5 is a rear elevational view thereof;
FIG. 6 is a left-side elevational view thereof; and,
FIG. 7 is a bottom plan view thereof.

The broken lines shown in the drawings illustrate portions of
the article that form no part of the claimed design.
